WOMAN'S SHOE

Wiley Robert Ecton, Towson, Md., assignor to Dixon-Bartlett-Lambrecht, Inc., Baltimore, Md.

Filed Sept. 29, 1970, Ser. No. 25,262

Term of patent 7 years

Int. Cl. D2—04

U.S. Cl. D2—297

FIG. 1

FIG. 2

FIG. 3

FIG. 1 is a front perspective view of a woman's shoe showing my new design;

FIG. 2 is a side elevational view thereof, and

FIG. 3 is a rear elevational view.

I claim:

The ornamental design for a woman's shoe, as shown and described.
